(57) **CLAIM**

The ornamental design for a steering wheel spoke, as shown and described.

DESCRIPTION

FIG. 1 is a front perspective view of a steering wheel spoke showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a right side elevational view thereof;

FIG. 7 is a front perspective view of the steering wheel spoke of FIG. 1, shown in a second environment;

FIG. 8 is a rear perspective view of the steering wheel spoke of FIG. 1, shown in the environment of FIG. 7;

FIG. 9 is a front perspective view of the steering wheel spoke of FIG. 1, shown in a third environment; and,

FIG. 10 is a rear perspective view of the steering wheel spoke of FIG. 1, shown in the environment of FIG. 9.

The left side elevational view is a mirror image of the right side elevational view.

The broken lines show portions of the steering wheel spoke which form no part of the claimed design.
